Primary Examiner — Katherine A Holbrow*Assistant Examiner* — Riya Salil Kamat(74) *Attorney, Agent, or Firm* — David & Raymond Patent Firm; Raymond Y Chan(57) **CLAIM**

The ornamental design for a toy keyboard tray for tablet, as shown and as described.

DESCRIPTION

FIG. 1 is a perspective view of a toy keyboard tray for tablet showing my new design.

FIG. 2 is a front view thereof.

FIG. 3 is a rear view thereof.

FIG. 4 is a left end view thereof.

FIG. 5 is a right end view thereof.

FIG. 6 is a top view thereof.

FIG. 7 is a bottom view thereof; and,

FIG. 8 is a perspective view showing the claimed design in use.

The broken lines depict portions of the toy keyboard tray for tablet that forms no part of the claimed design.
